GIOVANNI EMANUELE ELIA, OF PARIS, FRANCE, ASSIGNOR TO VICKERS LIMITED, OF WESTMINSTER, LONDON, ENGLAND.

AUTOMATIC FIRING DEVICE FOR SUBMARINE MINES.

1,025,905.

Specification of Letters Patent.

Patented May 7, 1912.

Application filed March 20, 1912. Serial No. 634,929.

To all whom it may concern:

Be it known that I, GIOVANNI EMANUELE ELIA, of Hotel de Crillon, Place de la Concorde, Paris, in the French Republic, have 5 invented certain new and useful Improvements in and Relating to Automatic Firing Devices for Submarine Mines, of which the following is a specification.

This invention has for its object the production of an automatic firing device for submarine mines in which the cocking and the firing are produced automatically by contact between the mine and the hull of a moving ship.

15 The invention consists more particularly in utilizing for the cocking and for the percussion, the buoyancy of the mine itself which enables the firing device to act at all depths and at all temperatures.

20 The accompanying drawing shows a vertical sectional view of a constructional form of a firing device embodying the invention.

A box *a*, which may be cylindrical in form 25 for example, comprises at its lower part a detonator *b* of suitable form intended to be lodged in the known manner in proximity to the explosive charge of a mine of ordinary construction; through this box there passes a vertical rod *c* ending at its lower part in a ring *d* to which a cable is fixed; this may be the cable by means of which the mine is moored and which exerts a given effort upon this rod.

35 The rod *c* comprises two sections which pass through stuffing boxes *e* *g* so that watertight joints are formed and these sections are united inside the chamber *a* by means of a yoke *f*. A double plate *h* is arranged at the upper extremity of this rod and the end 40 *i* of the lever *j* mounted upon a pivot *k* rigid with the box *a* engages in this plate; this extremity *i* is adapted to be held in engagement with the double plate *h* in any known manner, for example by means of a block of 45 sal ammoniac or other substance soluble in sea-water. The yoke *f* is mounted in a similarly shaped casing *l* provided with a protuberance *m* located opposite a nose *n* on a leaf spring *o* which is fixed at *p* to the wall of the box *a* and carries in proximity to its free end a striker *q* arranged opposite a cap *r* held in the yoke *f* and casing *l*. The casing *l* is filled with powder to form an explosive fuse *s* and is provided with an open-

ing *l'* opening into the tube *b'* containing the fulminate *t* of the detonator *b*. The detonator is suitably arranged in proximity to the explosive charge of the mine proper, which is not represented.

60 The operation is as follows:—When the mine is moored the traction exerted by the cable (not shown) upon the ring *d* of the rod *c* and due to the buoyancy of the mine, merely serves to maintain the mine as a 65 whole in the desired position of immersion, this tractive effort being transmitted by the double plate *h*, the rod *i*, *j* and its pivot *k* to the mine itself. The locking device constituted by the sal ammoniac or the like, 70 which locks the lever *i*, *j*, in place disappears after a certain time and releases this lever, the parts occupying the position represented in the drawing. The striker is at a suitable distance from the cap *r* and the spring *o* 75 carrying it is not cocked. When a ship strikes the mine, the friction against the hull causes the mine to rotate about its vertical axis and the lever *j* striking against the ship's side this lever turns about its pivot *k* 80 and its end *i* is disengaged from the double plate *h*. As this plate is no longer supported, it descends suddenly under the tractive effort exerted upon its ring *d*. During the first part of this movement the protuberance *m* bears upon the nose *n* in cocking the spring *o*, the parts then occupying 85 the position represented in broken lines. As the structure constituted as a whole by the lever *c* *f* continues to descend, the nose 90 *n* escapes from the protuberance *m* and the leaf spring *o* rises suddenly and projects the striker *q* into the cap *r* which by the intermediary of the quick match or fuse *s*, and of the fulminate *t* ignites the detonator *b* and 95 consequently the explosive charge of the mine.

100 The advantages are as follows:—This arrangement renders it possible to cock the mine only at the moment at which its action is desired and the certainty of operation is increased owing to the construction of the device itself, which does not comprise parts sensitive to variations of temperature and owing to the absence of springs or other 105 parts which require adjustment at the time of mooring while their strength may diminish owing to fatigue or for other reasons. Furthermore this device is exceedingly reliable in its operation; the buoyancy 110

of the mine itself is utilized as the motive power for actuating the striker and this buoyancy remains substantially constant; notwithstanding the variations of temperature due to differences of climate and to depth of immersion of the mine the buoyancy is substantially constant. It is also impossible for the detonator to be affected by the explosion of one or more adjacent mines and sea currents do not exert any effect upon it.

The safety device constituted by the lever *i j* may be replaced by any equivalent part adapted to be momentarily locked while being arranged in position. Instead of arranging this rod in such a manner as to permit it to release only the rod *c*, it might be arranged in such a manner as to cause it to slice through a pin or rupture a part of any kind so as to prevent the oxidation which may possibly be caused by the sea-water affecting the operation of the device by preventing the rod from sliding.

The invention is applicable to submarine mines of all kinds.

Claims:

1. A percussion device for sub-marine mines, comprising a box, a rod mounted to slide in the box and formed of two sections connected by a yoke piece, the lower end of said rod being adapted to be connected with the mooring cable, a casing in which the said yoke piece is mounted, provided with a projection, a leaf spring secured to the box and provided with a nose in the path of the said projection and with a striker, a cap carried by the casing and adapted to be engaged by the strikers of the spring, and a locking device for said rod.
2. In a percussion device for sub-marine mines, a box, a sliding rod mounted in the box and adapted to be connected with a mooring cable, a striker secured to the box, means carried by the rod and coacting with

the striker when released, a grooved member on one end of the rod, and a pivoted locking lever on the casing and having one end engaging the groove of said member.

3. A mechanism of the class described comprising a casing, a rod mounted to slide in the casing with its ends projecting through said casing, and to one end of which a mooring cable is adapted to be secured, a striker carried by the casing, a cap carried by the rod, means for maintaining the casing and rod in fixed position, and means for engagement with the said striker when the parts are moved relatively to each other, whereby the striker will be moved and permitted to engage the cap on its return travel.

4. A mechanism of the class described comprising relatively movable parts, one of the parts carrying a detonator, the said part also carrying a striker resiliently mounted in position, the other of the said parts carrying a cap, means for maintaining the parts in position and against movement relatively to each other, the said means being releasable, whereby the parts may move relatively to each other, the said part which carries the cap being provided with a projection coöperating with the said striker when the parts are moved, whereby the striker is brought remote from the cap, the striker returning from such remote position after movement through a suitable distance has been effected, the striker engaging the said cap, there being combustible material between the cap and the said detonator.

In testimony whereof I have hereunto placed my hand at London, England this twenty-ninth day of February 1912.

GIOVANNI EMANUELE ELIA.

In the presence of two witnesses:

EUSTACE H. BARKER,
ARTHUR T. WAGHORN.
